UNITED STATES PATENT OFFICE.

CARL SCRABIC, OF URBANA, OHIO.

TALKING MACHINE.

Application filed April 28, 1920. Serial No. 377,219.

To all whom it may concern:

Be it known that CARL SCRABIC, a citizen of the United States, residing at Urbana, in the county of Champaign and State of Ohio, 5 has invented certain new and useful Improvements in Talking Machines, of which the following is a specification.

This invention relates to sound reproducing machines, and has particular reference to 10 the amplifier construction thereof, the primary object of the invention being to provide an improved amplifying unit for talking machines in which features are provided for insuring a full and complete development 15 of sound vibrations imparted thereto, the structure aims particularly to provide means for effecting a reproduction of all of the various notes provided on the talking machine record by eliminating harsh and 20 metallic discords and by developing and bringing forth not only the fundamental tones but also the fine and delicate overtones or partials.

The invention consists more particularly 25 in the provision of an amplifier particularly adapted for use in conjunction with talking machines, said amplifier being formed from a resonant material and of such form as to constitute a somewhat ex- 30 tended outwardly flaring tube, in the narrow end of which sounds are initially introduced in order that the same may be gradually expanded, developed and enhanced in tone upon their delivery from the 35 outlet end of the amplifier.

Another object of the invention resides in combining an improved sounding board structure in conjunction with the amplifier, the walls of said structure being spaced 40 from the amplifier and united for resonance therewith by means of bridge strips, the construction being such that the fundamental tones may be developed within the amplifier, and the fine over-tones will be 45 produced and brought out by the sounding board structure.

A further object of the invention resides in unitarily connecting the amplifier and sounding board structure, in order that the 50 same may be deposited as a unit within the cabinet of a talking machine, the construction being such that the amplifier and sounding board may be constructed separately from the cabinet of a talking machine in 55 order to obtain facility in manufacture and to permit the parts of the talking machine

to be readily assembled in a completed state, provision also being made to insulate the resonant walls of the sounding board from the walls of the cabinet in order that the 60 vibration of the resonant bodies may be accomplished without being extraneously influenced by non-resonant surfaces.

A still further object resides in providing the amplifier with a plurality of telescopic 65 hollow combs so disposed as to be directly in contact with sound waves passing through the amplifier, said combs being spaced from the walls of the amplifier and are capable of resonating synchronously with said walls 70 by means of the provision of rigid bridge members, the presence of said combs in the amplifier results in increasing the resonating area of the amplifier as a whole and is therefore capable of assisting in the development 75 of sound vibrations.

With these and other objects in view, as will appear as the description proceeds, the invention further consists in the novel features of construction, combinations of elements and arrangement of parts, herein-after to be fully described and to have the scope thereof pointed out in the appended 80 claims.

In the accompanying drawings, forming a 85 part of this specification, and in which similar characters of reference denote like and corresponding parts:

Figure 1 is a vertical longitudinal sectional view taken through a talking machine constructed in accordance with the 90 principles of the present invention.

Figure 2 is a transverse horizontal sectional view taken along the plane disclosed 95 by the line 2-2 of Figure 1.

Figure 3 is a front elevation of the outlet end of the amplifier.

Figure 4 is a detailed side elevation of the amplifier disclosing more particularly 100 the structural development.

Figure 5 is a horizontal, sectional view taken along the line 5-5 of Figure 4, and,

Figure 6 is a detailed sectional view taken along the line 6-6 of Figure 4.

Referring more particularly to the details 105 of the invention, the numeral 1 designates the talking machine comprising the present invention in its entirety. This machine preferably consists of an upright cabinet 2 of any suitable and ornamental exterior configuration. In the form illustrated, the cabinet 2 is formed to embody vertically extend- 110

ing upright corner posts 3 which are united by means of side and rear walls 4, a bottom 5 and a top 6, all of which serve to enclose the reproducing mechanism of the talking machine.

Horizontally disposed within the cabinet is a shelf 7, below which is located a record filing case 8 and a motor chamber 9. This chamber is provided with any suitable type of motor 10, either spring or electrical, whose shaft 11 protrudes upwardly through a bearing provided in the shelf 7 and is adapted to carry the usual turn table or other rotatable record support 12. The winding shaft 13 of the motor 10, if the latter is of the spring type, protrudes forwardly and is equipped with a telescopic handle 14, the latter, when idle, is normally disposed to lie within a recess 15 provided in the front wall 16 of the chamber 9. When in use, the handle 14 is moved outwardly to a position independent of the wall 16, in order that said handle may be conveniently grasped to effect its rotation. This construction of the handle permits the latter to disappear, as it were, when not in use and by its position, the same will not form an objectionable projection upon a talking machine when not in use. Further, the record case 30 is closed by means of one or more hinged doors 17 which serve to cover the interior of the case 8 and to thereby enhance the general appearance of the cabinet construction. The turn table 12 is situated above 35 the shelf 7 and is located within a tone arm compartment 18 which is defined by means of upright walls 19 and a horizontal top 20. This cabinet is closed by means of a hinge door construction 21. Located within 40 the compartment 18 is the usual swinging tone arm 22, which is pivotally carried in a suitable bearing 23 provided in the shelf 7. The outer end of the tone arm is equipped with the usual sound box 24, which 45 is movable into engagement with the grooves of a record capable of being carried upon the turn table 12 in the ordinary manner.

From this description, it will be obvious that the machine 1 may be operated in a 50 very simple and convenient manner. The location of the compartment 18 is such that its interior parts may be readily handled by one who is occupying a seated position. In the average talking machine of the type 55 under discussion, it is necessary for the operator to be continuously stooping over or bending in order to reach various mechanisms and parts. However, by the arrangement of parts in the present invention, 60 it will be obvious that the record may be removed from the case 8, deposited upon the turn table 12, the motor may be suitably wound and the sound box and tone arm adjusted without requiring the operator to 65 move from a seated position. This accessi-

bility in arrangement renders the manipulation of the machine 1 a matter which is very convenient in actual performance and eliminates all undue fatigue and exertion.

Communicating with the outlet end of the 70 tone arm 22 is the reduced smaller end of a tubular amplifier 25. This amplifier forms one of the salient elements of the present invention and as previously stated, its construction is such as to develop and amplify 75 sound waves or vibrations imparted thereto and to clearly bring out all of the fine tonal shades and over-tones of the composition being reproduced. To this end, the amplifier 25 consists of a tubular tapering body which 80 is formed to include a horizontal portion 26, a communicating and continuous vertical portion 27 and a widely flaring mouth portion 28, the portions 27 and 28 being connected by means of a sound dome 29. 85 This amplifier is preferably formed from a resonant material, for example, thin dry wood, and to produce the peculiar construction thereof shown in the drawings, the amplifier is composed of a plurality of inter- 90 fitting pieces 30. These pieces are transversely curved to produce the tubular formation of the amplifier and the longitudinal joints 31 are formed after the manner disclosed in Figure 6. In other words, the 95 joint 31 is produced by beveling the overlapping meeting ends 32 of each piece 30 for a relatively extended distance and the joint is then completed by securely connecting in any suitable manner these overlapping 100 beveled ends. The end joints 33 of the pieces 30 are similarly formed, as shown in Figure 5, or in other words, the end walls of each piece are beveled as at 34 to cooperate with similarly beveled walls provided 105 upon the complementary end of an adjoining piece. This results in an interfitting telescopic joint which may be firmly connected, if desired, by mere frictional pressure and the joints may be completed by 110 rigidly connecting the wedge faces 34 in any suitable manner. It will be noted that the faces 34 are so disposed that the joints defined therebetween will extend backwardly 115 from their position of communication with the interior of the amplifier. This construction is such that sound waves passing through the amplifier will be prevented from escaping unduly from the amplifier by way of the joints 31 or 34, thereby confining the 120 sound vibrations for proper expansion within the amplifier. This construction results in enabling the peculiar curvature of the amplifier to be readily effected and enables the amplifier to be formed from the desired 125 resonant material, namely thin wood. The gradual outwardly flaring tubular construction of the amplifier is another important feature of the invention, in that the sound waves are permitted to gradually and prop- 130

erly expand before being delivered from the amplifier and by being caused to travel through the somewhat extended length of the latter, said sound waves will have their 5 intensity and magnitude accordingly enhanced in value. The presence of the dome construction 29 is also very important in the formation of the amplifier, in that it adapts the latter to the natural flow laws 10 governing the passage of sound, eliminates eddy conditions within the amplifier and distinctly tends to clarify and increase the carrying properties of the sounds emanating from the amplifier. In acoustic value, 15 the dome 29 may be likened to the overhead construction of a speaking stage or to the wall of a band stand. The mouth of the amplifier may be covered, if desired, by the usual foraminated screen 35.

20 In order to increase the resonanting area of the amplifier, the vertical portion 27 of the latter in this instance is provided with a plurality of hollow conical members 36 which are located in nested or telescopic 25 order, the walls of said members being spaced from each other and also from the walls of the amplifier. These conical members are held in place by means of bridge pieces 37, which rigidly unite said members 30 with the adjacent wall portions of the amplifier. Preferably, the members 36 are formed from a thin resonanting material, and by the presence of the bridge pieces 37, the same will vibrate in harmony with the walls 35 of the amplifier. It will be observed that the members 36 are so positioned as not to impede the progress or flow of sounds through the amplifier but on the other hand are so arranged as merely to insure the engagement 40 of the surfaces of said members with the sound vibrations. This results in increasing the resonance of the amplifier without disturbing or obstructing the flow of the sound waves.

45 Cooperative with the amplifier 25 is an improved sounding board structure 38. This structure consists of a suitable frame 39, which is built around the amplifier so that the amplifier and sounding board structure 50 will constitute a unit in the construction of the talking machine. This frame is of such construction as to entirely surround all sides of the amplifier portions 27 and 28 with sounding boards. These sounding boards 55 constitute spaced pairs of flat resonanting bodies or walls 40, which are securely mounted for vibration within the frame 39. The inner of the walls 40 are connected for vi-

bration with the adjacent walls of the amplifier 25 by means of bridge pieces 41, and similar pieces 42 are disposed between the walls 40 to insure their harmonious vibration. 60

From the foregoing it will be manifest that the present invention provides a structure possessing exceptional resonanting properties for the purpose of amplifying and developing sound waves produced from a talking machine record. The amplifier 25 itself will practically develop the fundamental tones reproduced by the instrument, 65 and through the provision of the sounding board structure, means have been provided for insuring the reproduction of delicate tone tints and expressions, such for example as the over-tones and accompanying partials. 70 These over-tones find vent through a perforated wall 43 located within the cabinet 1 contiguous to the outlet end of the amplifier. Moreover, by the construction of the 75 amplifier, metallic and nasal notes usually to be found in talking machine renditions are avoided, and on the contrary, full, round and resonating notes are to be obtained. The frame 39 is preferably provided with rubber bottoms or the like 44, which retain the 80 amplifier structure in place within the cabinet and prevent the resonant walls of said structure from coming into direct engagement with the walls of the cabinet. 85

In view of the foregoing description, 90 taken in conjunction with the accompanying drawings, it will be manifest that the present invention provides a talking machine of considerable utility and one capable of carrying out the above recited aims and objects. While the form of the invention herein shown and described is what is believed to be the preferred embodiment thereof, it is nevertheless to be understood that various forms, modifications and arrangement of 95 the parts may be made without departing from the spirit and scope of the invention as claimed. 100

With is claimed is:

In a talking machine, an amplifier, a housing extending around the amplifier, and spaced therefrom to provide a chamber, sound resonating boards disposed in spaced relation and located in the chamber and adjacent its inner walls, bridge pieces connecting the innermost boards and amplifier, and bridge pieces arranged in the space between said boards and connecting the confronting faces thereof. 105

In testimony whereof I affix my signature.
CARL SCRABIC. 110
